UNITED STATES PATENT OFFICE.

JOHN K. CAMPBELL, OF HARTFORD, CONNECTICUT.

MEANS FOR LUBRICATION OF WRIST-PINS.

980,597.

Specification of Letters Patent.

Patented Jan. 3, 1911.

Application filed August 19, 1910. Serial No. 577,916.

To all whom it may concern:

Be it known that I, JOHN K. CAMPBELL, a citizen of the United States, residing at Hartford, in the county of Hartford and 5 State of Connecticut, have invented certain new and useful Improvements in Means for Lubrication of Wrist-Pins, of which the following is a specification.

My invention relates to improvements in 10 means for lubrication of wrist pins and is particularly applicable to engines, pumps and compressors of the vertical type employing splash lubrication for the cylinder and piston and the objects of my improvements are simplicity and economy in construction and convenience and efficiency in use.

In the accompanying drawings:—Figure 1 is a longitudinal sectional view, certain 15 parts being shown in side elevation, of a pair of cylinders and pistons combined with a common inclosed crank case embodying my improved means of lubrication of the wrist pins. Fig. 2 is a side elevation of one 20 of the pistons and wrist pins shown in Fig. 1, viewed from the side in longitudinal alignment with the wrist pins, on an enlarged scale. Fig. 3 is a view of the same 25 turned 90 degrees and one side of the piston being shown in section. Fig. 4 is a bottom view of the same. Fig. 5 is a sectional view of an end of the wrist pin and the adjacent portions of the piston. Fig. 6 30 is a similar view of a modification of the 35 wrist pin. Fig. 7 is a side elevation of a piston and wrist pin in the position shown in Fig. 2, showing a modification of the piston. Fig. 8 is a view of the same turned 40 90 degrees. Fig. 9 is a bottom view of the same. Fig. 10 shows a piston having a 45 modification of the groove shown in Fig. 7 and in the same position as in said figure. Fig. 11 is a similar view of another modification of the same. Fig. 12 is a view similar 50 to Fig. 1 of a pair of pistons and cylinders and connected parts in which the connecting rod moves on the wrist pin and involving

vided on the upper side with a pair of openings 20 which communicate with the cylinders B attached to the said crank shaft casting. C is a crank shaft having bearings 21 60 in the end walls 22 of the said crank case A, and having intermediate the said bearings a pair of cranks 23. Connecting rods D connect the said cranks 23 with the pistons E, which operate within the said cylinders B, 65 the lower end being connected to a crank pin in the usual manner and the upper end fixedly secured by a set screw F to the wrist pin G at its center, which latter is operatively received in bearings 24 in the body of 70 the said piston E. The said wrist pin G may have a squared end 25 as shown in Figs. 4 and 5, or the end may conform to the section of a sphere 25^a as shown in Fig. 6, and furthermore the length may be such as to 75 provide clearance between the same and the wall 27 of the cylinder B as shown in Fig. 1, all of which conditions serve to provide a free space between the end of the wrist pin G and the wall 27 of the cylinder B and 80 which space is suitable for receiving oil and from which space the said oil may be delivered to the wrist pin G and the bearings 24 therefor for lubricating the same. The said crank case A is generally inclosed below the 85 said cylinders B and the bottom 28 is suitable for retaining a supply of oil into which the said cranks 23 and connecting rods D will dip in the course of their travels. Accordingly at each revolution of the crank a 90 quantity of oil will be splashed about in the crank case A and some will be thrown upward within the cylinder B and against the wall 27 of the same. The piston E in 95 its travels wipes the oil adhering to the said wall 27 and is thereby lubricated in an ordinary manner. By slabbing off the piston E longitudinally below the hole or bearing 24 provided for the wrist pin G as shown at 29 the oil adhering on the said wall 27 in alignment with the wrist pin is wiped off by the upper wall 30 of the said hole or bearing 100 and is either delivered directly to the said

mation of this slabbed off portion may however be changed and may be actually slabbed off from a turned piston or may be formed in the casting from which the cylinder is made. As described the said slabbed off portion 29 is located in alinement with the ends of the wrist pin and consequently the portions of the wall 27 of the cylinder from which the wrist pin G receives its supply of oil are located one on each side of the plane of travel of the connecting rod D and the crank 23. In Figs. 7, 8, 9, 10 and 11 the slab 29^a is at a position turned 90° degrees from the axial line of the wrist pin G and the wrist pin oil space or chamber, similar to 31^a shown in Fig. 12, is closed at the bottom and generally completely inclosed by the walls 27 of the cylinder and the walls 32 of the piston E fitting the same and end of the wrist pin. The slab 29^a extends from the bottom 33 of the piston E upward and terminates at its upper end in a groove 34 in the circumference of the cylinder so that oil will be delivered by the said groove to the wrist pin G and the said oil chamber 31^a. In Fig. 7 the said oil groove 34 is horizontal. The groove 34^a shown in Fig. 10 has a slight inclination in the direction of the wrist pin G, sufficient to insure the flow of oil toward the same and the groove 34^b shown in Fig. 11 has a greater and more pronounced inclination toward the wrist pin.

In Figs. 12, 13, 14, and 15 are shown a piston E¹ in which the wrist pin G¹ is rigidly secured by set screws F¹ adjacent the ends and to the centers of which wrist pin the connecting rod D¹ is operatively connected by a bearing 24^a. The slab 29^a and the groove 34^a are generally similar to those shown in Fig. 10 and deliver oil to the oil chamber 31^a. In order to deliver oil from the said oil chambers 31^a along the stationary ends 35 of the wrist pin G¹ and to the bearing 24^a intermediate the said ends I provide an open oil duct 36 which as shown extends along the entire length of the top side of said wrist pin G¹. This duct 36 accordingly serves as a direct means of supplying oil directly from the circumferential groove 34^a and oil chamber 31^a to the wrist pin bearing 24^a. The wrist pin oil chamber 31^a may be filled with oil, a continuous supply being maintained to replenish any that may be used in normal operation and a supply of oil will be retained therein when the apparatus is shut down so that a supply of oil is insured for the wrist pin that is immediately available as soon as the same is started in operation.

The device described as embodying my invention is an internal combustion engine. My invention is also applicable to engines of other types and also to pumps and compressors in which splash lubrication is employed.

It is apparent that some changes from the specific construction herein disclosed may be made and therefore I do not wish to be understood as limiting myself to the precise form of construction shown and described, but desire the liberty to make such changes, in working my invention, as may fairly come within the spirit and scope of the same.

I claim as my invention:—

1. In combination with a cylinder and a piston operative therein and a crank case opening into the said cylinder, a crank shaft operative in said crank case and having a crank, said crank case adapted to hold a supply of oil of a height suitable for the said crank to dip therein during normal operation so as to splash said oil against the walls of the said cylinder, a connecting rod connecting said crank and the said piston, the means of connection of the said piston and connecting rod comprising a transverse opening through said piston and intermediate its ends a wrist pin, the said wrist pin located intermediate the ends of the said piston and received in said opening the said piston generally fitting the said walls of the said cylinder and being slabbed off at the side from one end for a portion of the length, to said wrist pin hole.

2. A cylinder open at one end and having means for splashing oil along the interior walls thereof, a piston operative in the said cylinder, fitting the same generally and provided with a transverse opening in which is received a wrist pin, means for delivering oil from the said walls of the cylinder directly to the said wrist pin.

3. In combination with a cylinder means for splashing oil against the walls thereof during normal conditions of operation, a piston operative in said cylinder, transverse opening through the said piston, a wrist pin received within the said opening, oil spaces between the said interior walls of the cylinder and the ends of the wrist pin, and means for supplying oil from said interior walls directly to the said oil spaces.

4. A cylinder open at one end and having means for splashing oil along the interior walls thereof, a piston operative in the said cylinder and generally fitting the same, a wrist pin located in the said piston and forming a means of connecting a connecting rod, openings extending from the ends of the said wrist pin outwardly through the side walls of the said piston, the said piston slabbed off for a portion of its length so as to leave clearance between the same and the cylinder wall, and means for delivering oil from the said clearance space directly to the said openings.

5. A cylinder open at one end and having means for having oil splashed against its interior walls during normal conditions

of use, a piston operative in the said cylinder, fitting the said cylinder walls generally, having a portion of the sides slabbed off from one end along the length in the line of travel, and provided with wrist pin oil chambers, means for delivering oil from the said slabbed off portion to the said oil chambers.

6. In a reciprocating device of the single acting vertical, inclosed type having a cylinder, a piston operative therein, a crank shaft having a crank, a connecting rod connecting said piston and crank, a wrist pin serving as a means of connection of the said piston and connecting rod, the said crank serving during normal conditions of operation to

splash oil against the lower walls of the said cylinder, the said piston slabbed off longitudinally from the crank case end to approximately the height of the said wrist pin 20 so as to provide a clearance oil space between the said piston and the said cylinder walls, the upper end of said clearance space connected to the said wrist pin, the limiting wall of the said piston at the said upper end 25 a fit for the said cylinder so as to operate to deliver accumulations of oil from the said walls of the said wrist pin.
